WATCH BRACELET COMPONENT OR SIMILAR ARTICLE

Kurt Speck, Palisades Park, N.J., assignor to Jacques Kreisler Manufacturing Corporation, North Bergen, N.J., a corporation of New Jersey

Filed Mar. 10, 1965, Ser. No. 84,199

Term of patent 7 years

(Cl. D45—4)

FIGURE 1 is a perspective view of a watch bracelet component or similar article showing my new design.

FIGURE 2 is a top plan view thereof on an enlarged scale.

FIGURE 3 is a side elevational view taken on line 3—3 of FIG. 2.

FIGURE 4 is a fragmentary sectional view on a further enlarged scale taken on line 4—4 of FIG. 2.

I claim:

The ornamental design for a watch bracelet component or similar article, substantially as shown.
